CLEARANCE MARKER LIGHT FOR VEHICLES

William L. Mappes, Cincinnati, Ohio, assignor to North-east Capital Corporation, New York, N. Y., a corporation of New York

Application January 13, 1958, Serial No. 49,216

Term of patent 14 years

(Cl. D48—32)

Figure 1 is an elevational view of a clearance marker light for vehicles, showing my new design.

Figure 2 is a cross-sectional view taken along line 2—2 of Figure 1.

Figure 3 is an enlarged fragmentary sectional view taken along line 3—3 of Figure 1.

I claim:

The ornamental design for a clearance marker light for vehicles, substantially as shown.
